UNITED STATES PATENT OFFICE.

GEORGE A. REACH, OF PHILADELPHIA, PENNSYLVANIA.

DESIGN FOR A SIGN.

No. 38,294.

Specification for Design.

Patented Oct. 23, 1906.

Application filed September 6, 1906. Serial No. 333,577. Term of patent 14 years.

To all whom it may concern.

Be it known that I, GEORGE A. REACH, a citizen of the United States, residing at Philadelphia, Pennsylvania, have invented a new, original, and ornamental Design for Signs, of which the following is a specification, reference being had to the accompanying drawing, forming a part thereof, the figure, in elevation, showing my new design.

I claim—

An ornamental design for a sign, as shown.

GEORGE A. REACH.

Witnesses:

LINWOOD K. MOSES,
EDWARD A. CLUNGEON.
